UNITED STATES PATENT OFFICE.

FRANK T. SKOGLAND, OF MINNEAPOLIS, MINNESOTA.

DESIGN FOR A COMBINATION-TOOL.

48,014.

Specification for Design.

Patented Oct. 19, 1915.

Application filed May 17, 1915. Serial No. 28,766. Term of patent 7 years.

To all whom it may concern:

Be it known that I, FRANK T. SKOGLAND, a citizen of the United States, residing at Minneapolis, in the county of Hennepin and State of Minnesota, have invented a new, original, and ornamental Design for a Combination-Tool, of which the following is a specification, reference being had to the accompanying drawing, forming part thereof.

Figures 1 and 2 are opposite face views of a combination tool embodying my design.

I claim:

The ornamental design for a combination tool, as shown.

FRANK T. SKOGLAND.

Witnesses:

C. K. LAW,
H. C. NICHOLS.
